UNITED STATES PATENT OFFICE.

MORTIMER NORDEN, OF NEW YORK, N. Y., ASSIGNOR TO JOSEPH NORDEN, OF NEW YORK, N. Y.

COMBINED ATTACHMENT-PLUG AND BASE.

1,143,306.

Specification of Letters Patent. Patented June 15, 1915.

Application filed April 24, 1914. Serial No. 834,064.

To all whom it may concern:

Be it known that I, MORTIMER NORDEN, a citizen of the United States, residing in the borough of Manhattan, in the city, county, and State of New York, have invented an Improvement in Combined Attachment-Plugs and Bases, of which the following is a specification.

My invention relates to a combined electrical attachment plug and base and is an improvement upon the device shown in my co-pending application, Serial No. 799,659, filed Nov. 7, 1913, its object being to dispense with the rods integral with the right angled contact plates, also to dispense with the set screws for clamping said rods within the recesses in the plug, and to provide a means for connecting the contact plates to the plug in a manner to prevent loosening and to more positively hold the conductor wires in contact with the plates.

The details and operation of the invention are hereinafter particularly described.

In the accompanying drawing: Figure 1 is a plan view of my combined attachment plug and base connected together, in which the main conductor wires are shown in broken lines. Fig. 2 is a vertical section on the line $\alpha-\alpha$ of Fig. 1, showing the plug and base attached to a connection box, and Fig. 3 is an inverted plan view of the combined base and plug, the branch conductor wires being in section.

Similar reference numerals indicate like parts throughout the several views.

The plug 1 and its base 2 are both made of porcelain or other insulating material.

The base 2 is preferably of circular formation, having an integral angular flange 3, and a central opening 4 with oppositely disposed recesses 5 for the reception of the plug 1 and its contact pieces.

6 6 are lugs of insulating material, preferably made integral with the base, one of which lugs projects in line with the side wall of one of the recesses 5 at its right hand side, while the other lug projects in line with the other recess 5 at its left hand side.

7 7 are spring contact clips of metal located upon the top surface of the base 2, which clips are curved to conform to the shape of the base and the central opening

therein. The free ends of these spring contact clips 7 are bent slightly upward for 55 the purpose hereafter described.

8 8 are metallic contact plates arranged adjacent to the respective lugs 6, and placed over and in contact with one end of each of the said spring contact clips 7. Screws 9 60 pass through holes in the base and clips and screw into screw threaded holes in the plates 8.

10 10 are metallic binding screws screwing into screw threaded openings in the 65 plates 8 and through openings in the clips 7 and into screw threaded openings in the base. These binding screws 10 are for holding the main line wires 11 to the plates 8 on the base 2, the insulating material being removed from said wires a short distance to allow the bared portions of the wires to be looped around the binding screws 10 under their heads, so that when the screws are forced down to place the main wires are 75 brought into intimate contact with the plates; one end of each plate 8 is upturned to assist in holding the bared line wires in position. The flange 3 of the base is provided with screw holes 12 for the attachment of the base to a connection box 13, or other foundation by screws 14.

The plug 1 has a neck or portion of reduced diameter 15 adapted to enter and fill the central opening 4, in the base 2. There 85 is a central opening 16 extending entirely through the plug 1 through which pass the branch conductor wires 17. On the top surface of the plug 1 at opposite sides of the central opening therein, are recesses 18, extending to the outer surface of the neck of the plug, and into these recesses are inserted metallic contact plates 19, the ends of which adjacent the central opening are slightly upturned. These contact plates 19 95 extend a predetermined distance at right angles beyond opposite sides of the neck of the plug. The bottom of the plug is preferably provided with a recess 20 and on opposite sides of the central opening through 100 the plug and in line with the recesses therein longitudinal bores 21 are made, extending entirely through the plug, the lower part of such bores having a squared portion 22. The contact plates 19 are provided with 105 holes registering with the bores 21, and into

such holes and through the bores 21 there are inserted headed bolts 23 23, provided on their lower ends with a screw thread.

24 24 indicate nuts into which the screw threaded ends of these bolts 23 are screwed, the nuts 24 being within the squared portions 22 of the bores 21. The heads of the bolts 23 are provided with a transverse notch or groove for manipulation with a 10 screw driver.

The insulating material is removed from the ends of the branch conductor wires 17 which project beyond the top of the plug 1, and the bared wires are twisted around the 15 bolts 23 under their heads and, when the bolts are tightened intimate contact is made with the plates 19.

In connecting the plug 1 with its base 2, the projecting ends of the contact plates 19 20 are brought in line with the recesses 5 in the base, and the neck 15 of the plug is then pushed into the central opening 4 in the base, (the contact plates 19 at the same time passing into said recesses 5), until that portion of the plug having the larger diameter 25 comes into contact with the bottom of the base and prevents the further entrance of the plug, and in this position the extended ends of the contact plates 19 have passed 30 entirely through and out of the recesses 5 in the base. Now by giving the plug a partial rotation to the right, the contact plates 19 will pass under the spring contact clips 7 and remain in intimate frictional contact 35 therewith, thus forming both mechanical and electrical connection between the plug and its base. The bent up ends of the clips 7 assuring the free passage of the contact plates 19 beneath said clips. It will be seen 40 that the lugs 6 prevent the plug being rotated in the wrong direction.

In Fig. 2 of the drawing, I have illustrated the device as attached to a connection box, but it is obvious that the base may be 45 secured to any suitable support.

It will be seen that the bolts 23 serve to hold the contact plates 19 securely within the recesses 18 in the top of the plug and also form a means of binding the bared ends 50 of the branch conductor wires 17 to the contact plates 19. The nuts 24 being within the squared lower portions of the bores 21 are prevented from turning whereby the bolts 55 may be readily manipulated for releasing or binding the bared ends of the branch conductor wires.

I claim as my invention:

1. A plug of insulating material having a central opening extending entirely through 60 it for the reception of conductor wires, a longitudinal bore extending entirely through the plug on opposite sides of said central

opening, contact plates upon the upper end of said plug on opposite sides of the central opening extending at right angles thereto 65 and projecting a predetermined distance beyond the plug, each contact plate having an opening registering with said bores, headed bolts having screw threaded lower ends passing through said openings and through 70 said bores, nuts into which the screw threaded ends of the bolts are screwed, branch wires clamped between the heads of said bolts and said contact plates, in combination with a base of insulating material having 75 openings for the passage of said plug and right angled contact plates, metallic plates secured to said base for connection with an electric main, metallic spring clips in contact with said plates and secured to the base 80 and positioned to overlie and contact with the projecting ends of said right angled contact plates on a partial rotation of the plug and secure said projections between the clips and base. 85

2. A plug of insulating material having a recessed bottom, a central opening extending entirely through the plug for the reception of conductor wires, recesses in the top surface of the plug at opposite sides of said opening and extending to the outer surface of the plug, a longitudinal bore extending entirely through the plug on opposite sides of said central opening, the lower part of each bore being square, contact plates 90 seated in said recesses upon the upper end of the plug and extending at right angles thereto and projecting a predetermined distance beyond the plug, each contact plate having an opening registering with said bores, headed bolts having screw threaded lower ends passing through said openings and through 95 said bores, nuts within said square portions of said bores into which the screw threaded ends of the bolts are screwed, branch wires clamped between the heads of said bolts and said contact plates, in combination with a base of insulating material having openings for the passage of 100 said plug and right angled contact plates, metallic plates secured to said base for connection with an electric main, metallic spring clips in contact with said plates and secured to the base and positioned to overlie and contact with the projecting ends of said right angled contact plates on a partial rotation of the plug and secure said projections between the clips and base. 105

Signed by me this 8th day of December 110
1913.

MORTIMER NORDEN.
